CLAMP

Filed March 5, 1931

UNITED STATES PATENT OFFICE

JOHN F. ROBERTS, OF WEST PALM BEACH, FLORIDA

CLAMP

Application filed March 5, 1931. Serial No. 520,424.

The invention relates to clamps, and has for its object to provide a clamp particularly adapted for use by wood workers and constructed in a manner whereby the clamp body 5 may be clamped to a support at an angle to a member to which pressure is to be applied, and to provide the clamp body with a screw threaded therethrough at an angle for applying said pressure.

10 A further object is to provide a clamp comprising spaced registering members adapted to receive therebetween a support, guide pins carried by one of the members and slidably mounted transversely in the other member, 15 a threaded screw extending through said members and adapted to force said members together, a transversely disposed enlargement carried by one of said members, and through which the screw and guide pins extend, and to provide a pressure applying screw threaded through said enlargement transversely of the jaw at a right angle to the clamping screw and guide pins.

20 A further object is to provide a set screw threaded through the end of one of the members and cooperating with the end of the other member, and forming means whereby when the members are clamped on a support, 25 said members are held in substantial parallel relation for insuring a positive clamping operation.

A further object is to provide the cooperating jaws of the clamping members with threaded lugs extending inwardly and adapted to imbed in a support for holding the same against pivotal movement when pressure is applied to a member to the side of the clamp.

30 With the above and other objects in view the invention resides in the combination and arrangement of parts as hereinafter set forth, shown in the drawings, described and claimed, it being understood that changes in the precise embodiment of the invention may 35 be made within the scope of what is claimed without departing from the spirit of the invention.

In the drawings:

Figure 1 is a perspective view of the clamp showing the same on a support and adjacent

a member to which pressure is to be applied.

Figure 2 is a vertical longitudinal sectional view through the clamp and a support.

Figure 3 is a vertical transverse sectional view through the clamp.

55 Referring to the drawings the numeral 1 designates a support and 2 a member disposed in the side thereof, and for purposes of illustration at a right angle thereto, and to which member pressure is to be applied.

60 The clamp comprises an upper member 3 and a lower member 4. In wood working it is often desirable to apply pressure to a member at a right angle to a support, for instance in boat building, such a clamp is particularly 65 desirable as it can be clamped on the ribs and pressure can be applied to the planking before the riveting operation; however the clamp is applicable for general use. The clamp members 3 and 4, at their clamping ends, are 70 provided with threaded lugs 5, adapted to be imbedded into the support 1 when the members 3 and 4 are forced together by the clamping screw 6. Clamping screw 6 is rotatably 75 mounted in an aperture 7 in the upper clamp- 75 ing member 3 and threaded at 8 through the transverse enlargement 9 carried by the upper side of the lower member 4, and it will be seen when the operator rotates the handle member 10 carried by the clamping screw 6, 80 the clamping members 3 and 4 will be forced into close clamping engagement with the support 1, as clearly shown in Figure 2. During this clamping operation, the adjustable members 5 are imbedded into the opposite sides 85 of the support 1, therefore it will be seen that when transverse pressure is applied from the clamp to the member 2 by the pressure screw 10a, the clamp will be held against pivotal 90 movement on the support 1. The pressure screw 10a, it will be noted, is threaded through the enlargement 9 adjacent the clamping screw 6, and the guide pins 11, therefore it will be seen that the transverse 95 strain is in the enlargement and adjacent the pins 11 and set screw 6.

One end of the pressure screw 10a is provided with a handle 12, adapted to be grasped by the operator for rotating the pressure screw 10a for applying pressure to the mem- 100

ber 2 through the usual pivoted head 13 carried by the screw 10a.

The outer end of the lower member 4 is provided with an enlargement 14, through 5 which is threaded at 15 a set screw 16. The upper end of the set screw 16 engages the outer end of the member 3 at 17, and by adjusting the screw 16 the positive clamping of the support 1 is insured and at the same time 10 the engagement of the members 3 and 4 with the support 1 in parallelism is made possible.

The lugs 5 are threaded through the members 3 and 4, and if it is desired to eliminate the same, for instance where there is a finish 15 on the support 1, they can be unscrewed from either or both sides to prevent marring of the finish.

From the above it will be seen that a clamp 20 is provided which is particularly adapted for use by wood workers, and which clamp is provided with means whereby pressure may be applied to a member at an angle, for instance at a right angle to the support and to the clamp, thereby providing a positive 25 clamping and holding device, which will work at various angles. Although the member 2 is shown at a right angle to the clamp and support, it is obvious that pressure could be applied to a member at any angle to the 30 support. The right angle position is shown for purposes of illustration only.

The invention having been set forth what is claimed as new and useful is:—

1. A clamp adapted to be received on a 35 support, said clamp comprising spaced jaws, a clamping screw extending through said jaws and forming means for forcing the same towards each other, guide pins carried by one of said jaws and slidably mounted in the 40 other jaw, said clamping screw and guide pins being in the same plane, a transverse enlargement carried by one of said jaws and through which said pins and clamping screw extend, and a pressure screw extending trans- 45 versely through said jaw and enlargement and forming means whereby pressure may be applied to a member disposed to one side of the jaw.

2. A clamp adapted to be received on a sup- 50 port, said clamp comprising spaced jaws in parallel relation, adjustable support imbed- 55 ding lugs carried by said jaws, a set screw at one end of one jaw and cooperating with the end of the other jaw, a clamping screw spaced inwardly from the set screw, guide pins carried by one of the jaws and slidably mounted in apertures of the other jaw, a transverse enlargement carried by one of the 60 jaws and through which the clamping screw and guide pins extend in the same plane and a pressure screw extending transversely through said enlargement in a plane parallel to the plane of the clamping screw and pins, and adjacent the clamping screw and pins, 65 and forming means whereby pressure may

be applied to a member located to one side of the clamp.

3. A clamp adapted to be received on a support, said clamp comprising spaced jaws, a clamping screw extending through said 70 jaws and forming means for forcing the same towards each other, guide pins carried by one of said jaws and slidably mounted in the other jaw, said clamping screw and guide pins being in the same plane, and a pressure screw extending transversely through one of the jaws and forming means whereby pressure may be applied to a member disposed to one side of the jaw.

4. A clamp adapted to be received on a 80 support, said clamp comprising spaced jaws in parallel relation, adjustable support em- 85 bedding lugs carried by said jaws, a set screw at one end of one jaw and cooperating with the adjacent end of the other jaw, a 90 clamping screw spaced inwardly from the set screw, guide pins carried by one of the jaws and slidably mounted in apertures of the other jaw, said clamping screw and guide pins being in the same plane and a pressure screw extending transversely through one of the jaws adjacent the clamping screw and pins and forming means whereby pressure may be applied to a member located to one 95 side of the clamp.

In testimony whereof he hereunto affixes his signature.

JOHN F. ROBERTS.
